UNITED STATES PATENT OFFICE.

RALPH G. WHITLOCK, OF LOS ANGELES, CALIFORNIA.

LOOSE-LEAF BOOK.

1,228,860.

Specification of Letters Patent. Patented June 5, 1917.

Application filed July 6, 1916. Serial No. 107,764.

To all whom it may concern:

Be it known that I, RALPH G. WHITLOCK, a citizen of the United States, residing at the city of Los Angeles, in the county of Los Angeles and State of California, have invented new and useful Improvements in Loose-Leaf Books, of which the following is a specification.

My invention relates to a book consisting of a cover and means secured thereto for securing loose leaves therein, and the object thereof is to provide improved and simple means for removably securing the leaves in place within the cover which will also permit 15 of the removal of such leaves as it may at any time be desirable to remove, whether it is a part or all of such leaves.

A further object is to provide a back frame of such construction that it may be 20 opened and locked open by a lever on the end of the frame and may be locked shut by the same lever.

Another object is to construct the principal portions of the back frame by stamping the 25 parts from sheet metal.

In the drawings forming a part of this application:

Figure 1 is a front elevation, partly broken away, of a cover with my back frame 30 in place.

Fig. 2 is a section on the line 2—2 of Fig. 1.

Fig. 3 is an enlarged end elevation of the 35 back frame viewed from the opening lever end showing the back frame locked open.

Fig. 4 is a like view to Fig. 3, showing the back frame closed and locked.

Figs. 5 and 6 are side elevations of parts 40 of the back frame and the opening and locking lever in the open and closed positions.

Fig. 7 is a plan view of a sheet metal blank before it is formed into a back frame.

Figs. 8, 9 and 10 are details showing 45 parts of the blank formed into portions of the back frame.

In the drawings in Figs. 1 to 6 inclusive the back frame is shown as constructed of wire suitably formed. In the other figures the back frame is shown as constructed of 50 sheet metal suitably formed.

Referring to the drawings as shown in Figs. 1 to 6 inclusive, 15 and 16 are the side members of the back frame and are 55 preferably made of heavy wire the ends of which are turned at right angles to the body and hingedly connected by rod 17. At suit-

able distances along the body members and secured thereto are what may be termed deformed ring members which are composed of the body portions 18 which are cut on a line opposite rod 17, and form segments of a circle, and the shank members 19. These ring members are connected to the body members at the junction of the body portions with the shanks. The shanks project upwardly and inwardly and the shanks of each of the ring members are hingedly connected by rod 17, which, when the ring members are in their closed position lies a little above the plane that passes across the upper surfaces of the body members. Near one end of rod 17 and rigidly secured thereto is a transverse or fulcrum bar 20 on which bar is pivotally mounted an L-shaped lever by means of which the body members of the back frame are caused to approach each other whereby the ring members are opened. This L-shaped lever I term an opening lever and is composed of shanks 21, which are pivotally connected to the fulcrum bar, and the body member 22 lying at right angles to the shank members. The shanks are separated and a portion of the body member 22 is cut away so as to permit it to pass over the end of rod 17 when the ring members are opened.

Secured to shanks 21 is a locking lug 23 which passes between lugs 24 and 25 on body members 15 and 16. Locking lug 23 may be formed integral with the opening lever. 90 When the ring members are in their closed position shanks 21 lie in a plane parallel with the plane of the body members of the back frame and when the ring members are opened they lie in a plane at right angles to the plane of the body members of the back frame. Normally the ring members are in closed positions. By pressing on the top of the opening lever its shanks press against the body members of the back frame and force them toward each other thereby opening the ring members. In order to make a better attachment between the members of the back frame and the cover than has been heretofore possible I revolvably mount on the side members of the back frame strips 25^a of thin sheet metal, in which are rows of perforations 26 preferably placed along the edges thereof. The lining 27 of the cover is glued to the inner side of the strip and the outside member 28 of the cover is glued to the outer side of this strip. The glue will 105 110 115

fill the perforations in strip 25 and thereby forms, as it were, rivets from the lining to the outer member of the cover and passing through the perforations in strips 25. Strips 5 25 constitute hinge members for connecting the cover to the back frame. In order to close the ring members after being opened I provide springs 29 the ends of which are connected to the side members of the back 10 frame and the center is coiled around rod 17. These springs are preferably placed at the ring members nearest the ends of bar 17 and as the closing lever is returned to its normal position, which is the position shown in Fig. 15 6, return the members of the back frame to their normal position thus closing the ring members.

Fig. 7 shows a back frame and ring member blank being a piece of sheet metal 20 stamped to be formed into a back frame with ring members integral therewith.

Figs. 8, 9 and 10 show the blanks formed up into a back frame comprising members 30 25 and 31 and ring members having shanks 32 and body portions 33. A rod 34, being the same as rod 17 connects the parts. The ring members are integral with the back frame in this construction.

Having described my invention what I 30 claim is:

1. In a device of the character described, a back frame composed of parallel side members having ends bent inwardly; a rod passing through said bent ends and hingedly 35 connecting them; ring members connected to said side members; said ring members having outer portions the shape of a segment of a circle and shanks projecting inwardly and upwardly from said side members 40 and being revolubly mounted on the rod

connecting the ends of the side members; and springs coiled around said rod and having their ends bent around the side members.

2. In a device of the character described, a back frame composed of parallel side members having ends bent inwardly; a rod passing through said bent ends and hingedly connecting them; ring members connected to said side members, said ring members having outer portions the shape of a segment 45 of a circle and shanks projecting inwardly and upwardly from said side members and being revolubly mounted on the rod connecting the ends of the side members; springs coiled around said rod and having their ends 50 bent around the side members; a fulcrum bar mounted on said rod; and an L-shaped opening lever pivotally mounted on said fulcrum bar.

3. In a device of the character described 60 herein, the combination of a back frame having parallel side members hingedly connected by a rod extending from end to end and ring members mounted on the side members; with an L-shaped lever pivotally connected to said rod and adapted to be rocked so as to force the side members toward each 65 other, and thereby open the ring members.

4. In a device of the character described, a metal back frame composed of side members hingedly connected; and ring members secured to said side members, said ring members being hingedly connected in pairs with the centers of the hinges lying above 70 the plane of the centers of the side members.

In witness that I claim the foregoing I have hereunto subscribed my name this 30th day of June, 1916.

RALPH G. WHITLOCK.
